UNITED STATES PATENT OFFICE.

EDWIN E. SLICK, OF WESTMONT BOROUGH, PENNSYLVANIA.

AUTOMATIC VALVE.

1,248,026.

Specification of Letters Patent. Patented Nov. 27, 1917.

Application filed February 9, 1915. Serial No. 7,092.

To all whom it may concern:

Be it known that I, EDWIN E. SLICK, a citizen of the United States, residing in the borough of Westmont, in the county of Cambria and State of Pennsylvania, (whose post-office address is Johnstown, Pennsylvania,) have invented certain new and useful Improvements in Automatic Valves; and I do hereby declare the following to be a full, clear, and exact description of the invention, such as will enable others skilled in the art to which it appertains to make and use the same.

My valve is designed to automatically control the flow of fluids through ports or openings governed thereby, in blowing engines, air pumps, air compressors, or other fluid pressure mechanisms, and on account of its light weight and conformation, the valve moves with a minimum amount of inertia or momentum, and consequently is comparatively silent and free from destructive effects to itself, its seat or adjacent portions of the construction.

I prefer to form the moving part of my valve of a thin plate, preferably of steel or other metal, and in the illustration herewith, I have shown these valves as flat and annular, but they may be of any other outline such as elliptical, rectangular, or of other forms as will be readily understood. The moving part of the valve itself is normally held to its seat by a plurality of light springs which may be helical, leaf form, involute or other shape, but in any case they should be as light as possible in order to control the valve without undue pressure or violent action and the strength of the springs may vary, dependent somewhat on the speed and amplitude of their movement and pressures to be controlled.

The valve is seated upon a port or ports of outline corresponding to that of the valve itself but somewhat narrower, so that the edges of the valve overlap the port and in order to insure the proper registry of the valve and port, I provide stationary guides which contact with the edge or edges of the valve and maintain it in proper relation with the said ports during its backward and forward movement and when closed. I also provide a backing for the valve at a suitable distance from the seat which forms a stop for the valve at the desired limit of its opening motion.

My valves are thin and formed of com-

paratively narrow strips of metal of annular or other form and by reason of this they are very cheaply made and on account of their shape and proportions will not be subject to excessive stresses, strains or deflections and consequently will not be subject to destruction or breakage, whereas in valves of larger dimensions and other forms, the stresses and strains frequently exceed the elastic limits of the materials resulting in repeated breakages.

Owing to its annular form, my plate valve can be made from a slice of a round bar of steel or other metal, which is cut cross wise of its longitudinal axis. The center or inferior part of the metal can be punched out and thrown away and the exterior ring of superior metal can be used for the valve. If desired, this ring of outer metal cut from a round bar can be forged or otherwise drawn out thinner and of larger diameter, and then finished into its final form by machining and polishing. This latter practice gives a valve of the very best material and one which will not be subject to breakage, as it is composed of the very best part of the bar, and its narrow ring form and dimensions make the stresses therein well within its ability to withstand them.

Having thus given a general description of my invention, I will now, in order to make the matter more clear, refer to the annexed sheet of drawings, in which like characters and like figures denote like parts:

Figure 1 is a central cross sectional elevation of my automatic valve showing the annular valves, valve seats, guides, stop, springs, spring guides and other portions, this view being taken on the line I—I of Fig. 2.

Fig. 2 is a plan view of Fig. 1, showing an upper view of the valve-stop, with the annular valves themselves indicated by the larger dotted circles.

Fig. 3 is a plan view of the valve seat with the stop and valves removed for the sake of clearness of illustration.

Fig. 4 is a central cross sectional elevation of a slightly modified form of valve showing the use of leaf springs instead of the helical springs of Fig. 1, this being taken on the line IV—IV of Fig. 5.

Fig. 5 is a plan view looking within the valve-stop corresponding to Fig. 4, but with the seat portion removed showing the leaf

springs partly in and partly projecting from the interior annular groove and guide, while in this view the corresponding springs in the outer annular guide therefor have been removed to show the construction more clearly.

Fig. 6 is a side elevation of the leaf springs and their holder, which are adapted to fit in the outer annular groove of the valve stop of Figs. 4 and 5.

Fig. 7 is a plan view of the movable annular plate portions of my valve showing two of these rings, viz:—an inner and outer ring, this view being drawn on a reduced scale as compared with the other illustrations.

Fig. 8 is a side elevation of an involute inner spring which can be used with the form of valve shown in Figs. 4 and 5.

Fig. 9 is a perspective view of one of the spring casings or plungers corresponding to Figs. 1 and 2.

Referring now to the characters on the drawings:—

1 indicates a casing with valve seats formed on the upper surface thereof and annular ports therethrough, the valve seats being shown as annular in shape, 2 is an intermediate annular ring between the valve ports, 3 is the hub of the casing, 4 indicates a threaded opening formed in the hub, 5 represents radial ribs of the casing, 6, is the inner port in the valve casing, 7 is the outer port in the same, 8 is the outer ring of the stop and 9 are radial ribs to strengthen and stiffen the construction, the edges of which also form guides for the ring valves. 10 is the inner ring of the stop, 11 are enlarged sockets formed integral with the rings 8 and 10, provided with the holes 12 therein, which holes are adapted to relieve the air pressure within the sockets due to the backward and forward motion of the spring plungers therein, thereby permitting the valve to respond quickly to the pressures to which it is subjected. It will be noted that the stop rings 8 and 10 are flat on the surface which contacts with the annular disks and are preferably narrow so that they do not permit the compression of fluid between their surfaces and that of the disks. These stops limit the opening distance of the valves, but, by reason of their form and construction, have no other effect whatsoever, and the ample free space around them permits the fluid between them and the valve to escape immediately upon the approach of the valve. These stops, therefore, only limit the movement of the valves when the valves come into forcible contact with them.

In addition to this, it should be further noted that the ribs or guides 9 are comparatively narrow and merely contact with small portions of the edges of the annular disks in order to guide them, without in any

manner interfering with their free movement and without stopping the flow of the fluid or causing any compression thereof, which compression, if it occurred, would cause a sluggish movement of the annular disk valve.

In valves which have stops that are comparatively wide and particularly those stops which are not flat and which have downwardly projecting edges forming pockets, there is considerable resistance offered to the opening movement of the valve, due to the compressed fluid between the valves and the stop as the valve approaches its limiting position with the prejudicial result of offering increased resistance to the fluid passing through the port and causing a slow and sluggish action of the valve, which consequently does not open or close freely when it should, thereby causing irregularities in its action and loss of efficiency.

13 represents springs mounted in the sockets and provided with guide plungers 14 as shown, which plungers serve to keep the helical springs in position and reduce the possibility of their coils contacting with the edges of the sockets. In addition to the openings 12, I may also provide grooves 15 in the plunger, which serve a similar purpose. The inner and outer valves which are shown as plates of annular form are indicated as 16 and 17 respectively; while 18 is a threaded projection on the stop portion adapted to receive the female threaded portion of the valve casing hub 3, as shown.

Referring now to Figs. 4 and 5:—19 and 20 indicate an outer and an inner groove respectively, shown of annular form, adapted to contain the leaf springs and their holder, the sides of which grooves also serve to guide the springs during their backward and forward movement.

21 represents a spring holder which, by means of its bent portion 22, holds the leaf springs 23, as shown, while 24 is a form of involute spring which may be used in connection with the valves illustrated in Figs. 4 and 5.

The guides which contact with the edges of the valves and serve to maintain them in position during their movement are indicated as 25. The plate valves illustrated in any one group are shown in the same plane, but if desired, I may use a plurality of plate valves on different planes, the general shape of the structure thus being conical.

Although I have shown and described my improvements in considerable detail, I do not wish to be limited to the exact and specific details shown and described, but may use such substitutions, modifications or equivalents thereof, as are embraced within the scope of my invention, or as pointed out in the claims.

Having thus described my invention, what

I claim and desire to secure by Letters Patent is:—

1. A valve comprising an annular disk mounted on a seat and over a port of corresponding annular form, and a flat, substantially continuous stop centrally located with respect to and opposite said disk. 5
2. A valve comprising a plurality of thin annular disks concentrically mounted, a corresponding plurality of seats provided with ports of outline similar to but narrower than said disks, and flat, substantially continuous stops centrally located with respect to and opposite said disks, said stops being substantially parallel to the seats aforesaid. 10
3. A valve comprising an annular disk, a seat containing a port of corresponding form, narrow ribs adapted to guide said disk in its backward and forward motion, there- 15 by maintaining its registry with said port, and a flat, substantially continuous stop centrally located with respect to and opposite said disk. 20
4. A valve comprising an annular disk, a seat containing a port of corresponding outline but narrower than said valve, a flat, substantially continuous stop centrally located with respect to and opposite said disk, and springs mounted in said stop adapted to 25 contact with the back of the valve. 30
5. A valve comprising a flat annular disk, a seat having a port of outline corresponding to but narrower than said valve, a flat, narrow, substantially continuous stop centrally located with respect to and opposite 35

said disk, said stop being provided with enlargements, forming sockets, springs mounted in said sockets and adapted to contact with the back of the valve, and means for guiding said springs during their move- 40

6. A valve comprising a plurality of flat annular disks, a seat having ports of outline corresponding to but narrower than said valves, flat seats adjacent the edges of said ports adapted to coöperate with the disks and thereby close said ports, narrow, flat, substantially continuous stops centrally located with respect to and opposite said disks, and a plurality of springs mounted within 45 50 said stops adapted to hold said disks normally on their seats.

7. A valve comprising a plurality of flat annular disks, seat portions provided with ports of outline corresponding to but narrower than said disks, flat, substantially continuous stops centrally located with respect to and opposite said disks, and a plurality of springs mounted within said stops and adapted to normally hold said disks on their 55 60 seats, said springs being provided with plungers surrounding them and contacting with the outer ends of said springs and with the disks aforesaid.

In testimony whereof I hereto affix my 65 signature in the presence of two witnesses.

EDWIN E. SLICK.
